THERMOSTAT, SAFETY PILOT, AND
LIMIT CONTROL

Harold A. Mantz, Milwaukee, Wis., assignor to
Milwaukee Gas Specialty Company, Milwaukee,
Wis., a corporation of Wisconsin

Application January 29, 1943, Serial No. 473,968

16 Claims. (Cl. 236—21)

This invention relates to control systems and has to do more particularly with a system for heating a body of fluid by means of a burner and for controlling supply of fuel to the burner responsive to temperature variations of the fluid body being heated, while assuring that fuel supplied to the burner, after extinguishment thereof, will be ignited.

My invention is directed to a system comprising a main burner having associated igniting means, and operating means effective for shutting off the supply of fuel to the burner when the igniting means is rendered inoperable or when the temperature of the fluid being heated exceeds a predetermined maximum, the operating means being also responsive to the temperature of the fluid for shutting off the supply of fuel when the fluid is at a desired maximum temperature and reestablishing the supply of fuel when the fluid is at a desired minimum temperature, when the igniting means is operable. More specifically, I provide a main fuel supply control valve the opening and closing of which is controlled, under normal operating conditions, by the temperature of the fluid body, and means assuring closing of the valve and maintaining it closed upon failure of a pilot burner associated with the main burner, or when the temperature of the fluid exceeds the desired maximum, the latter means comprising an electromagnet energized by the heat of the pilot burner and reset means for setting the parts for normal operation.

I have illustrated the control system of my invention as applied to a water heater, by way of example, but it is to be understood that my invention, in its broader aspects, is capable of many other applications and may be used for controlling the temperature of water or any other liquid or fluid within an enclosed space or container. Further objects and advantages of my invention will appear from the detail description.

In the drawings:

Figure 1 is a side view, partly broken away and in section, of a hot water boiler and heater control means therefor embodying my invention.

Figure 2 is a central vertical sectional view, on an enlarged scale, of the control means of my invention, certain parts being broken away and certain parts being shown in elevation, with the parts in the positions they occupy when the control valve closing member is in its released or operable position; and

Figure 3 is a semi-diagrammatic sectional view on the order of Figure 2 but with the control valve

in open position and the closing member for that valve in its attracted or inoperable position.

The hot water tank 5 may be of any suitable known construction and is provided, a suitable distance from its lower end, with a domed bottom wall 8 beneath which is disposed a main gas burner 7, within a chamber 8 defined by the depending lower skirt portion 9 of the tank. Cold water is supplied to tank 5 through a down pipe 10 and hot water is withdrawn from the tank through a pipe 11. The burner 7 may be of any suitable known type and comprises a conduit 12 flared at its lower end to provide a mixing chamber 13 having a plate 14 provided with air admission openings and adjustable for regulating the amount of air admitted to chamber 14. Gas is supplied to mixing chamber 13 through a nipple 15 suitably mounted on the upturned end of a gas supply pipe 16 passing through an opening in skirt 9.

A valve body 20, shaped as shown, is mounted on tank 5, by means of an exteriorly threaded nipple 21 screwing through a boss 22 of the tank. Valve body 20 is separated interiorly into an inlet chamber 23 and an outlet chamber 24, by a partition 25 having a valve opening 26 therethrough surrounded at the inlet chamber side with a raised valve seat element 27. Bottom wall 28 of valve body 20 is suitably bored and tapped for reception of the upper end of pipe 16 screwed therewith and opening into outlet chamber 24, and for reception of a second gas supply pipe 29 screwing at its upper end into wall 28 and opening into inlet chamber 23. Pipe 29 is connected to a suitable source of supply of fuel gas, as will be understood, and is provided with a normally open shut-off cock 30 of known type.

Opening 26 is controlled by a valve comprising a cupped valve disc 31 at the inner face of which 40 is mounted an angular facing member 32, of leather or other suitable material, confined between disc 31 and a retaining washer 33 fitting about the reduced inner portion of a boss 34 projecting from the inner face of disc 31 and peened over at its inner end at 34A as shown. A relatively large cylindrical boss 35, extending from the outer face of valve disc 31, has a sliding fit in a cylindrical valve stop and closure member 36 provided, at its outer end, with a reduced outwardly tapering extension 37. This extension 37 is flanged inward at its outer end and there fits about the inner end portion of an operating stem 38 having, adjacent its inner end, a circumferential groove 39 which receives a resilient U-shaped retaining member 40 of known type. The member 36 is

thus attached to the inner end of stem 38 for outward movement with the latter. A stop plug 31a, threaded into the inner end of extension 31, assures inward movement of member 36 with stem 38 upon inward movement of the latter.

Stem 38 is slidable through an outwardly extending packing gland 42 of a cup-shaped inner section 43 of an electromagnet housing 44 having also an outer cylindrical section 45. The inner end portion of section 45 is offset outwardly slightly and has a push fit over the outwardly offset outer end portion of section 43. The section 45 is provided at its inner end with an outwardly extending circumferential flange 46 clamped between the outer end of an exteriorly threaded neck 47 projecting from the front of body 20, in which neck 47 section 43 fits closely, and a flanged nut 48 screwing on the neck, with an intervening sealing gasket 49. Gland 42 receives packing material 50 compressed by a washer 51 slidable on stem 38 and urged outward therealong by a coil compression spring 52 mounted about extension 31 of member 36 and stem 38, confined between the outer end of member 36 and washer 51. The housing 44 is thus effectively sealed off from inlet chamber 23 so as to guard the parts within housing 44 from the deleterious effects of the gas or other fluid in that chamber.

An armature 53 of suitable magnetic material is secured in a cradle 54 mounted on the outer end of stem 38, between two U-shaped retaining members 55, of known type, engaging in corresponding circumferential grooves 56 in stem 38. This mounting of the cradle 54 is a loose mounting permitting slight universal movement thereof in order that the armature may seat accurately on the pole ends of the frame of an associated electromagnet. A substantially U-shaped electromagnet frame 57, of suitable magnetic material, is supported within housing 44, by a bracket 58 secured to frame 57 and to the outer end of housing 45 by connector means, as will be explained presently.

The connector means is generally similar to the means disclosed in the Alfery Patent No. 2,276,909. It comprises an exteriorly threaded terminal bushing 59 extending through a corresponding opening in the outer end wall of housing 44 and provided at its inner end with an interior shoulder 60. A terminal member 61, mounted in bushing 59, is provided at its inner end with a reduced stud 62 extending through the inner end of bushing 59 and through the outer portion of bracket 58, from which and bushing 59 member 61 is insulated by a shell 63 of insulating material. A washer 64 of insulating material is disposed about stud 62, at the inner face of bracket 58, and one terminal lead 65 of a coil 66, mounted about one leg of frame 57, is extended between washer 64 and a metal washer 67 disposed about stud 62 adjacent the inner end thereof. The other terminal lead 68 of coil 66 is grounded to bracket 58, the outer portion of which seats against the inner end of bushing 59, and a sealing gasket 69 is disposed about the inner end portion of bushing 59 at the outer face of bracket 58. The inner end of stud 62 is peened over at 70, clamping tightly together the parts between the inner end of stud 62 and the inner end of bushing 59 in a manner effective for establishing good electrical connection between lead 65 and stud 62 and between bracket 58 and bushing 59, while also securing the stud 62 to the bushing 59. A nut 71 is screwed on bushing 59 in contact with the outer end wall of housing 44, with the adjacent portion

of that wall clamped between nut 71 and gasket 69, so that the connector assembly is secured to housing 44 with gasket 69 forming a fluid tight seal about the bushing 59.

5 A thermocouple 72 is disposed adjacent the main burner 7 in association with a pilot burner 73 for igniting fuel issuing from burner 7. The thermocouple may be of any suitable known type, but preferably is similar to that disclosed in the 10 Leins Patent No. 2,126,564. It comprises a hot junction 74 disposed to be heated by the flame of the pilot burner, an external metal tube 75 constituting a lead, connected at one end to the external element of the thermocouple, and an internal lead 76 connected at one end to the internal element of the thermocouple and extending through and insulated from tube 75. A metal thimble 77, flanged at its inner end, is secured upon the other end of tube 75 with its outer end portion within the correspondingly formed outer 15 end portion of a sleeve 78 through the outer end of which thimble 77 extends. A conical tip contact member 79 is secured upon the other end of lead 76 in concentric spaced relation to sleeve 78, with a washer 80 of insulating material fitting about lead 76 between the base of thimble 77 and the base of tip member 79, this washer also fitting 20 tightly within sleeve 78 and serving to hold tip member 79 spaced therefrom. Sleeve 78 is threaded 25 interiorly at its inner portion and when it is screwed on bushing 59 clamps stud 61 and tip member 79 together, with tip member 79 seating tightly in a corresponding recess in the outer end of stud 61, sleeve 78 then also serving to clamp thimble 77 to bushing 59 and to establish good 30 electrical connection therebetween, as will be clear from Figure 2. In that manner, the elements of the thermocouple 72 are connected to the terminal leads of the electromagnet coil 66 for energizing the latter, when the hot junction 35 74 of the thermocouple 72 is heated by the flame of the pilot burner 73.

3 A suitably formed lever 83 is pivoted at its mid-length for swinging movement in inlet chamber 45 23, on a pin 84 extending therethrough and mounted at its ends in the side walls of valve body 20. The lower portion of lever 84 straddles the valve stop and closure member 36 and is connected thereto, at opposite sides thereof, by pin and slot connections 85. The lever 83 is of approximately H shape, comprising two side arms, one of which is shown at 86, connected by a cross member 87 through which pin 84 passes. A block 88 is disposed between the upper ends of arms 86, to which it is connected by pin and slot means comprising a pin 89 passing through block 88 and extending, at each end, through a slot 90 in arm 86. A reset stem 91 is secured at its inner end to block 88 and extends therefrom outward through the outer or front wall of valve body 20, in concentric spaced relation to a surrounding nipple 92 projecting outward from that wall. Nipple 92 receives and guides a button 93 secured on the outer end of stem 91 and recessed from its inner end, for reception of the outer end portion of a coil compression spring 94 disposed about stem 91 and confined between button 93 and a washer 95, adjacent the inner end of nipple 92, through which stem 91 slides. Packing material 96, confined between the washer 95 and the inwardly tapering inner end of nipple 92, is compressed by spring 94 about stem 91 so as to provide a fluid tight seal thereabout.

75 The current generated by the thermocouple, when it is heated, energizes coil 66. The magnetic

field of the electromagnet is not of sufficient strength to move the armature 53 outward from its full line position shown in Figure 2, but is of sufficient strength to hold the armature 53 in its outward position when it has been moved into contact with the pole ends of the magnet frame 57. By pressing the reset button 93 inward, the valve stop and closure member 36 is moved outward and armature 53 is likewise moved outward into contact with the pole ends of magnet frame 57, in which position it is held by the electromagnet, if at that time the thermocouple 72 has been and is being properly heated.

A valve stem 97 is secured at its inner end in boss 34 of valve 31, and is slidably mounted, at its outer portion, in a boss 98 of back wall 99 of the valve body 20. Valve stem 97 is provided, at its mid portion, with a double cone element 100 of a size to pass through an opening 101 in the back wall of a cupped spring cage 102 in the inner end of which is suitably secured a retainer ring 103 defining an opening of proper size to accommodate element 100. An annular coil tension spring 104 is mounted within spring cage 102 about valve stem 97 and is confined between ring 103 and the back wall of cage 102, so as to be restrained against movement axially of the cage. Spring 104 has an interior diameter but slightly greater than the diameter of valve stem 97, when this spring is in its fully retracted position, as shown.

A valve operating lever 105 extends upwardly within chamber 24 of valve body 20, this lever being provided at its lower end with a fork defining two arms, one of which is shown at 106, which straddles valve cage 102 and are connected thereto, at opposite sides thereof, by pin and slot connections 107. Lever 105 is provided, adjacent its upper end, with two conical recesses 108 and 109 extending from its outer and inner faces, respectively, recess 109 receiving a conical point 110 of a setting screw 111 threaded through a boss 112 extending inward from the front wall of the upper portion of chamber 24. This portion of the front wall of chamber 24 is thickened at 113 and is suitably recessed for reception of a stuffing box 114 providing a fluid tight seal about the stem of the screw 111, the latter being provided at its outer or forward end with an enlarged knurled head 115 to facilitate adjustment thereof. Recess 108 receives a conical point 116 of a plunger 117 slidable through a boss 118 extending inward from back wall 99 of valve body 20 adjacent the upper end of this wall. Boss 118 is coaxial with nipple 21, which is provided with a stepped recess 119 extending from its outer end. The inner reduced portion of recess 119 receives the outer end portion of a metal tube 120 secured in nipple 21 by a pressed fit therein. A closure plug 121 is suitably secured in the inner end portion of tube 120, conveniently by a circumferential rib pressed inwardly from the tube into a corresponding groove formed in plug 121, there being a sealing cap 123, of suitable material, at the inner end of tube 120 and effecting a fluid tight seal thereof. A rod 124 is secured at its inner end in plug 121, conveniently by being screwed therein, this rod extending coaxially within tube 120 and seating, at its outer end, in a recess in plunger 117. Tube 120 has a greater coefficient of expansion than rod 124 and, when it contracts, forces rod 124 in an outward direction, that is, a direction toward the valve body 20, expansion of tube 120 causing movement of rod 124 inward, that is, in a direction away from the valve body 20.

It will be seen that point 116 of plunger 117 75

provides an upper fulcrum about which the lever 105 may swing in either direction in the adjustment of screw 111, point 110 of screw 111 providing a second and lower fulcrum about which lever 105 may swing in either direction responsive to expansion and contraction of tube 120. A coil compression spring 125 seats, at its outer end, in a recessed boss 126 of wall 99 and is confined between the outer end of this boss and a cupped follower 127, in which the inner end of spring 125 seats, provided with a conical point 128 engaging into a conical recess 129 extending from the outer face of lever 105 a short distance above the forked lower end portion thereof. Spring 125 urges lever 105 inward in a counterclockwise direction about point 110 of adjusting screw 111, as permitted by the position of plunger 117, and by adjusting screw 111 lever 105 may be adjusted by this screw, in cooperation with spring 125, in either direction about point 116 of plunger 117, for a purpose which will appear presently.

A supplementary housing 130, flanged at its inner end, is secured on the outer end wall of housing 44 in a suitable manner, conveniently by means of screws 131, with an intervening sealing gasket 132, housing 130 overlying an opening 133 through the outer or front end wall of housing 44. A corrugated metal bellows 134 is mounted within housing 130 by means of a nipple 135 flanged at its inner end, extending through the end wall of housing 130 and secured thereto by a nut 136 screwing on nipple 135 and clamping the adjacent portion of wall 137 between the flanged inner end of nipple 135 and nut 136.

The body of the bellows 134 is formed of metal corrugated to bellows shape, as stated, and is secured at its outer end to the flange at the inner end of nipple 135, by soldering or in any other suitable manner, to provide a fluid-tight and pressure-resistant seal therebetween. The other end of the body of the bellows 134 is soldered or otherwise suitably secured to a flange 138 at the inner end of a cylindrical head 139 extending into the body of the bellows and substantially filling the space therein surrounded by the corrugated bellows body. A trip finger 140, of generally L shape, is suitably secured at its outer end, conveniently by means of a screw 140a, to the inner end of head 139 and extends therefrom through opening 133 and along the outer side of the other leg of the magnet frame 57, that is, the leg thereof about which the coil 66 is not mounted. Coil 66 is provided, at each end thereof, with a disc 141 of insulating material, these discs 141 extending about and outward beyond the leg of magnet frame 57 along which the trip finger 140 extends. The discs 141 are slotted for reception of trip finger 140 and, together with the adjacent leg of magnet frame 57, guide this finger 140 in the reciprocatory rectilinear movement thereof. A tube 142, formed of copper or other suitable metal, is secured at one end within nipple 135, there being a wiping 143 of solder or other suitable material about the outer end of nipple 135 and the adjacent portion of tube 142 to provide a fluid-tight seal therebetween. Nipple 135 is provided with a restricted orifice 144 through its inner end opening into the interior of the bellows 134 for flow of fluid into and from the latter. Tube 142 is extended into the hot water tank 5, through a suitable stuffing box 145, providing a fluid-tight and pressure-resistant closure about the tube, and is secured at its other end to one end of a bulb 146 in free communication therewith, this bulb being sealed at its other

end and disposed within the tank 5 so as to be exposed to the temperature of the water or fluid within this tank. The bulb 146 and tube 142 contain a thermosensitive fluid, as does the bellows 134, which may be either liquid or gaseous, this fluid expanding responsive to increase in temperature and contracting responsive to decrease in temperature. The bellows 134 normally is held, by its inherent resiliency, in its collapsed condition shown in Figure 2, at which time the inner end of trip finger 140 is spaced outward a short distance from the inner end of the adjacent leg of the magnet frame 51. It will be noted from Figure 3 that the armature 53 is of somewhat greater extent than the magnet frame 51 and projects outward beyond the legs of this frame, the edge portion of armature 53 adjacent trip finger 140 being in the path of movement thereof when this finger is moved inward.

It is intended that the pilot burner 13 be lit at all times so long as the cock 30 remains in open position, so that the hot junction 74 of the thermocouple 72 is heated and the coil 66 of the electromagnet is energized. In Figure 2, the control valve closing and guide member 36 is shown in its inner or operable position, with the armature 53 released from the magnet frame 51 and spaced inwardly therefrom. Member 36 is then held in its inner or operable position by compression spring 52, supplemented by spring 94, closing the valve 31 and assuring that this valve is maintained in its closed position so long as member 36 remains in its inner or operable position. Closing of valve 31 interrupts flow of fuel to the main burner 7, with resulting extinguishment thereof. In order to reignite the main burner and set the control means into operation, the reset button 93 is pressed inwardly to a sufficient extent to move member 36 outward into its outer or inoperable position, with armature 53 seating against the pole ends of the magnet frame 51, as shown in Figure 3. Since the electromagnet normally is energized, the armature 53 is held thereby in its outer position, together with the valve closing and stop member 36, in opposition to the springs 52 and 94, both of which, at that time, are compressed, the strength of the magnetic field generated by the coil 67, when the thermocouple is heated by the pilot burner, being sufficient for that purpose. With the member 36 held in its outer or inoperable position, the hub 35 of valve 31 is slidable in member 36, and the valve 31 may be opened and closed independently of member 36. It may be assumed, for purposes of description, that member 36 is in its attracted outer position, as in Figure 3, and the valve 31 is in its closed position, into which it has been moved responsive to a desired maximum temperature of the body of fluid within the tank 5. Accordingly, under the conditions assumed, the water within tank 5 has been heated to the desired maximum temperature, and the supply of fuel to the main burner 7 has been cut off, thus extinguishing that burner. As the temperature of the water within tank 5 decreases, the tube 120 contracts and rod 124 is moved lengthwise toward the valve body 20, thus urging the lever 105 in a clockwise direction about the point 110 of adjusting screw 111. That results in moving the spring cage 102 and the parts carried thereby outward along the valve stem 97 toward wall 99, the spring 104 moving along the double cone element 100 and being expanded radially thereby during such movement. As the

spring 104 passes over the central portion of element 100, that is, the portion thereof of maximum diameter, it contracts about the outwardly tapering outer portion of element 100 and forces stem 97 inward with a snap action, until the valve 31 is in its outermost position in contact with the valve stop and closing member 36, at which time valve 31 is in its full open position, shown in Figure 3. That reestablishes flow of fuel to the main burner 7, which is reignited by the pilot burner 13 for again heating the water in tank 5. The burner 7 then functions to heat the water in tank 5, and as the temperature of the water increases the tube 120 expands, moving rod 124 outward and permitting movement of lever 105 in a counterclockwise direction about the point 110 of adjusting screw 111. During this movement of lever 105 valve stem 97 is restrained against inward movement, by contact of valve 31 with member 36, as in Figure 3, and remains stationary until spring 104 passes over the center of element 100, at which time this spring contracts about the inner inwardly tapering portion of element 100 and moves the valve 31 into its closed position, with a snap action. Valve 31 is held closed until the temperature of the water within tank 5 decreases to a desired predetermined minimum, at which time the spring 104 passes outwardly beyond the center portion of element 100, again opening valve 31 in the manner previously described. By adjusting the screw 111 the desired minimum and maximum temperatures at which opening and closing of the valve 31 will occur, responsive to the temperature of the water within tank 5, may be varied so that the control may be set for any desired minimum and maximum temperatures, within limits. The control means thus provides comparatively simple and safe means for automatically turning on and off the main burner 7 responsive to desired minimum and maximum temperatures of the water within tank 5.

The thermoresponsive trip means, comprising the valve 146 and bellows 134 and associated parts, provides safety means assuring extinguishment of the main burner 7 in the event of failure of the lever 105 and associated parts, for any reason, to close valve 31 when the temperature of the water within tank 5 reaches the desired predetermined maximum. In such case the water within the tank could be heated to a temperature in excess of the desired maximum, and objectionably high pressures with resulting damage or injury might occur. In the event of the water within tank 5 being heated to an objectionably high temperature, in excess of the predetermined desired high temperature, the expansion of the fluid within bulb 146 and tube 142 and bellows 134 causes expansion of the latter, moving the trip finger 140 inward along the adjacent leg of the magnet frame 51, into contact with the armature 53. As the trip finger 140 continues to move inward, it forces the armature 53 away from the pole ends of the magnet frame, thus releasing it therefrom, and member 136 is moved inwardly, by the expansive force of spring 52 supplemented by the expansive force of spring 94. The combined strength of these two springs is adequate to overcome such resistance to outward movement of valve stem 97 as may be offered by the spring 104, which latter spring is disposed at the outer portion of element 100 in the open position of valve 31, and as the central portion of element 100 passes outward beyond spring 104 the action of this latter spring

supplements the action of the springs 52 and 94 for closing the valve, and thereafter the springs 104 and 52 and 94 cooperate to assure that the valve 31 is maintained in its closed position. In order that the valve 31 may again be placed under control of lever 105, after the condition which prevented closing of the valve has been remedied, the valve closing and stop member 36 is reset to its inoperable position by pressing the reset button 93 inwardly, as above described. Extinguishment of the pilot burner 73 results in cooling of the hot junction 74 of the thermocouple 72, with resulting deenergizing of coil 66 of the electromagnet so as to release the armature 53, the member 36 being then moved inward into its operable position effective for closing valve 31 and maintaining it closed in the manner above described. Valve 31 cannot thereafter be reopened until member 36 is reset into its inoperable position in the manner above explained. In order to effect the resetting operation, it is necessary that the pilot burner be lit in order to heat the hot junction of the thermocouple, and that the resetting button 93 be maintained in its inner position, holding armature 53 in contact with the pole ends of the magnet frame 57, until the hot junction of the thermocouple has been heated sufficiently to generate electric current for energizing the coil of the magnet and thereby holding armature 53 in its outer position. That means that the resetting operation cannot be completed until the condition causing extinguishment of the pilot burner has been remedied and the pilot burner has been relighted. Accordingly, no fuel can be supplied to the main burner 7 unless the pilot burner is lit, which eliminates danger of fuel being supplied to the main burner and escaping therefrom without being ignited.

The control means of my invention comprises, briefly, a main burner and means normally operable for controlling supply of fuel to the main burner responsive to different temperatures generated by such burner, means for shutting off flow of fuel to the main burner responsive to an objectionably high temperature generated thereby, and means under control of the pilot burner adjacent the main burner for igniting the latter and receiving fuel in advance of the means for controlling the supply of fuel to the main burner, the pilot burner controlled means being effective for assuring closing off of the fuel supply for the main burner responsive to failure of the pilot burner. While I prefer to employ the thermostat means shown and above described for opening and closing the fuel control valve responsive to desired predetermined minimum and maximum temperatures generated by the main burner, and also prefer to use the thermostat means shown and described for assuring closing of the fuel supply control valve responsive to an objectionably high temperature generated by the main burner, any other suitable means may be used, in either case, within the broader aspects of my invention. It will be understood that changes in construction and arrangement of parts of my invention may be resorted to, without departing from the field and scope thereof, and I intend to include all such variations, as fall within the scope of the appended claims, in this application in which the preferred form only of my invention is disclosed.

I claim:

1. In a control means of the character described a main burner, a fuel supply conduit therefor, a valve controlling flow of fuel through

said conduit, means subject to heat generated by said main burner for opening and closing said valve responsive to a desired minimum and a desired maximum temperature, a pilot burner for igniting said main burner connected to said conduit in advance of said valve, a valve closing member movable to an inoperable position permitting opening and closing of said valve and yieldingly urged toward an operable position assuring closing of said valve and maintaining it closed, means, comprising an electromagnet connected in circuit with a thermocouple subject to the heat of said pilot burner and an armature for said electromagnet, effective for holding said member in its inoperable position when the pilot burner is lit and for releasing it upon extinguishment of said pilot burner, and means subject to heat generated by said main burner for releasing said armature from said electromagnet and thereby said member from its inoperable position responsive to a temperature in excess of the desired maximum.

2. In control means of the character described, a main burner, a fuel supply conduit therefor, a valve controlling flow of fuel through said conduit, a first thermoresponsive means subject to heat generated by said burner for opening and closing said valve with a snap action responsive to a desired minimum and a desired maximum temperature, a pilot burner for igniting said main burner connected to said conduit in advance of said valve, a thermoelectric generator heated by the flame of the pilot burner, a valve closing member movable to an inoperable position permitting opening and closing of said valve and yieldingly urged toward an operable position assuring closing of said valve and maintaining it closed, said member in its inoperable position providing a stop limiting opening of said valve, an armature connected to said valve closing member for holding it in its inoperable position, an electromagnet energized by said thermoelectric generator effective when energized for holding said armature in its attracted position, said electromagnet when energized being ineffective for moving said armature from its released position to its attracted position, resetting means for moving said valve closing member from its operable position to its inoperable position and thereby moving said armature from its released position to its attracted position, said resetting means including means yieldingly urging said valve closing member toward its operable position, and a second thermoresponsive means subject to heat generated by said main burner for releasing said armature from said electromagnet responsive to a temperature in excess of the desired maximum.

3. In control means of the character described, a valve body comprising an inlet chamber and an outlet chamber with a valve port therebetween, a valve controlling said port, a stem secured at one end to said valve extending therefrom into said outlet chamber and slidably therein at its other end portion, a valve operating lever mounted in said outlet chamber for swinging movement and yieldingly urged in one direction, thermostat means operatively connected to said lever for swinging it in the other direction and permitting swinging movement thereof in said one direction responsive to decrease and increase in temperature, cooperating means carried by said lever and said valve stem effective for opening and closing said valve responsive to movement of said lever in said other direction and in said one direction, a valve closing member having an inoperable position permitting opening and closing of said valve

and yieldingly urged toward an operable position effective for closing said valve and maintaining it closed, an armature connected to said member for holding the latter in its inoperable position, an electromagnet effective when energized for holding said armature in its attracted position and thereby holding said valve closing member in its inoperable position, said electromagnet being ineffective for moving said armature from its released position to its attracted position, reset means for moving said valve closing member from its operable position to its inoperable position and thereby moving said armature to its attracted position, and a second thermostat means effective for releasing said armature from said electromagnet responsive to a predetermined high temperature.

4. In control means of the character described, a valve body having an inlet chamber and an outlet chamber with a valve port therebetween, a valve controlling said port, a stem secured to said valve extending therefrom into said outlet chamber, a valve operating lever mounted in said outlet chamber, means comprising a thermostat for swinging said lever in opposite directions responsive to decrease and increase in temperature, said valve stem being provided with an element tapering from its central portion toward each end of said stem, means disposed about said stem for relative movement lengthwise thereof comprising a radially expandible and contractible member disposed for engagement with the inclined areas of said element and effective by contraction thereof for urging said stem and valve axially in closing and opening directions, a valve closing member in said inlet chamber having an operable position effective for assuring closing of said valve and maintaining it closed and an inoperable position permitting opening and closing of said valve by said resilient member, connections between the latter member and said lever for imparting movement to said resilient member lengthwise of said valve stem in accordance with movement of said lever, an armature connected to said valve stop member for holding the latter in its inoperable position, an electromagnet effective when energized for holding said armature in attracted position and thereby holding said valve closing member in inoperable position, said electromagnet being ineffective for moving said armature from released position to attracted position, a second thermostat means effective for releasing said armature from said electromagnet responsive to a predetermined objectionably high temperature, and reset means for moving said valve closing member from its operable position to its inoperable position and thereby moving said armature into attracted position, said reset means comprising means yieldingly urging said valve closing member toward its operable position.

5. In control means of the character described, a valve body having an inlet chamber and an outlet chamber with a valve port therebetween, a valve controlling said port, a stem secured to said valve extending therefrom into said outlet chamber, said stem being provided intermediate its ends with a double conical element tapering from its center portion toward the ends of said stem, a spring cage disposed about said stem, a radially expandible and contractible resilient member mounted in said cage cooperating with the tapered surfaces of said element for moving said stem and valve in opening and closing directions, an operating lever connected to said cage for moving the latter lengthwise of said

stem, means comprising a thermostat for swinging said lever in opposite directions responsive to predetermined minimum and maximum temperatures, a valve closing member having an inoperable position permitting opening and closing of said valve and yieldingly urged toward an operable position effective for closing said valve and maintaining it closed, electromagnetic means for holding said valve closing member in its inoperable position, and thermostatic means for releasing said valve closing member from said electromagnetic means responsive to an objectionably high temperature.

6. In control means of the character described, 15 a valve body having an inlet chamber and an outlet chamber with a valve port therebetween, a valve controlling said port, a valve stem secured to said valve extending therefrom into said outlet chamber, said stem being slidably mounted at its outer end portion in said valve body, a lever mounted in said outlet chamber, said lever and said valve stem being provided with cooperating means for opening and closing said valve responsive to movement of said lever from one position to another position, means comprising a 20 thermostat for moving said lever from said one position to said other position and vice versa responsive to a desired predetermined minimum and maximum temperature, said valve having a 25 coaxial projection at the inlet chamber side thereof, a valve closing member coaxial with said valve slidably receiving said projection, means yieldingly urging said valve closing member into operable position effective for assuring closing of said valve and maintaining it closed, a stem attached at its inner end to 30 said valve closing member for moving the latter outward into an inoperable position permitting opening and closing of said valve, said valve closing member when in its inoperable position receiving and guiding said projection of said valve and providing a stop limiting opening of said valve, an armature attached to the outer end of 35 said second stem, an electromagnet effective when energized for holding said armature in attracted position and thereby holding said valve closing member in its inoperable position, and means comprising a second thermostat for releasing 40 said armature from said electromagnet responsive to an objectionably high temperature.

7. In control means of the character described, 45 a valve body having an inlet chamber and an outlet chamber with a valve port therebetween, a valve controlling said port, thermostresponsive means for opening and closing said valve responsive to a predetermined low temperature and a predetermined high temperature, a valve closing member having an inoperable position permitting opening and closing of said valve and an operable position effective for assuring closing of said valve and maintaining it closed, said member when in its inoperable position slidably receiving and guiding a portion of said valve and limiting movement thereof in opening direction, an armature attached to said valve closing member for holding it in its inoperable position, an electromagnet effective when energized for holding said armature in attracted position but ineffective for moving said armature from its released position to its attracted position, reset means for moving said valve closing member to its inoperable position and thereby moving said armature to its attracted position, said reset means comprising means yieldingly 55 urging said valve closing member toward its op-

erable position, and thermostat means for releasing said armature from said electromagnet responsive to a temperature in excess of said desired maximum temperature.

8. In control means of the character described, a valve body having an inlet chamber and an outlet chamber with a valve port therebetween, a valve controlling said port, thermoresponsive means for closing and opening said valve responsive to a desired maximum temperature and a desired minimum temperature, a valve closing member having an inoperable position permitting opening and closing of said valve and an operable position assuring closing of said valve and maintaining it closed, said member having a sliding connection with said valve for guiding the latter in its opening and closing movement when said valve closing member is in its inoperable position, an abutment member, a stem attached at its inner end to said valve closing member and slidable through said abutment member, an armature attached to the outer end of said stem, an electromagnet effective when energized for holding said armature in its attracted position but ineffective for moving said armature from its released position to its attracted position, said armature and said stem holding said valve closing member in its inoperable position when said armature is in its attracted position, a compression spring confined between said abutment member and said valve closing member urging the latter toward its operable position, a lever in said inlet chamber pivoted between its ends connected at one end to said valve closing member for moving the latter to its inoperable position and thereby moving said armature to its attracted position, a reset stem slidable through a wall of said inlet chamber and connected to the other end of said lever for moving said valve closing member to its inoperable position upon inward movement of said stem, means comprising a compression spring about said reset stem urging the latter outward of said valve body, both of said springs being compressed and coacting to urge said valve closing member into its operable position when said armature is in its attracted position, and thermoresponsive means for releasing said armature from said electromagnet responsive to a temperature in excess of said desired maximum.

9. In control means of the character described, a valve housing having an inlet chamber and an outlet chamber with a valve port therebetween, a valve controlling said port, thermoresponsive means for opening and closing said valve responsive to a desired predetermined minimum temperature and a desired predetermined maximum temperature, a valve closing member having an inoperable position permitting opening and closing of said valve and an operable position assuring closing of said valve and maintaining it closed, an armature attached to said member for holding it in its inoperable position when said armature is in attracted position, an electromagnet effective when energized for holding said armature in attracted position but ineffective for moving said armature from its released position to its attracted position, said electromagnet comprising a magnet frame, resetting means for moving said valve closing member from its operable position to its inoperable position and thereby moving said armature from its released position to its attracted position, a normally collapsed bellows fixed at one end to said valve body, a trip finger attached to the other end of said

bellows slidable thereby along said magnet frame and disposed to contact said armature and force the latter away from the magnet frame and thereby release it, when said trip finger is moved in one direction by expansion of said bellows, said reset means comprising yielding means urging said valve closing member toward its operable position, and thermoresponsive means connected to said bellows for causing expansion thereof responsive to a temperature in excess of said desired maximum.

10. In control means of the character described, a valve body having an inlet chamber and an outlet chamber with a valve port therebetween, a valve controlling said port, thermoresponsive means for opening and closing said valve responsive to a predetermined desired minimum temperature and a predetermined desired maximum temperature, a valve closing member in said inlet chamber having an inoperable position permitting opening and closing of said valve and an operable position assuring closing of said valve and maintaining it closed, an armature attached to said member for holding the latter in its inoperable position, an electromagnet effective when energized for holding said armature in its attracted position, said electromagnet being ineffective for moving said armature from its released position to its attracted position, reset means for moving said valve closing member from its operable position to its inoperable position and thereby moving said armature from its released position to its attracted position, said reset means comprising means yieldingly urging said valve closing member toward its operable position, and thermoresponsive means comprising a bellows and a trip member actuated thereby for forcing said armature away from said electromagnet and thereby releasing it therefrom responsive to a temperature in excess of the desired maximum.

11. In control means of the character described, a valve body having an inlet chamber and an outlet chamber with a valve port therebetween, a valve controlling said port, thermoresponsive means for opening and closing said valve, a valve closing member having an inoperable position permitting opening and closing of said valve and an operable position assuring closing of said valve and maintaining it closed, a reset lever pivoted between its ends connected at one end to said valve closing member for moving the latter into its inoperable position, an abutment member, a stem attached at one end to said valve closing member and slidable through said abutment member, an armature attached to the other end of said stem, an electromagnet effective when energized for holding said armature in its attracted position but ineffective for moving said armature from its released position to its attracted position, a pilot burner, a thermocouple connected in circuit with said electromagnet and subject to the heat of said pilot burner, a reset stem slidable through a wall of said inlet chamber connected to the other end of said lever, a compression spring confined between said abutment member and said valve closing member, a compression spring about said reset stem urging the latter outward, inward movement of said reset stem moving said valve closing member into its inoperable position and thereby moving said armature into its attracted position, both of said springs being compressed and cooperating to urge said valve closing member toward its operable position when said armature is in its attracted

position, and condition responsive trip means for releasing said armature from said electromagnet for movement of said armature to released position and movement of said valve closing member to operable position.

12. In control means of the character described, a valve body having an inlet chamber and an outlet chamber with a valve port therebetween, a valve controlling said port, condition responsive means for mechanically opening and closing said valve responsive to a first condition and a second condition, a valve closing member having an inoperable position permitting opening and closing of said valve and an operable position effective for mechanically closing said valve and maintaining it closed, electromagnetic means effective when energized for holding said valve closing member in inoperable position but ineffective for moving said valve closing member from its operable to its inoperable position, condition responsive means for releasing said valve closing member from said electromagnetic means and moving it to operable position, and reset means for moving said valve closing member from its operable to its inoperable position.

13. In control means of the character described, a valve body having an inlet chamber and an outlet chamber with a valve port therebetween, a valve controlling said port, means for mechanically closing and opening said valve responsive to a predetermined high temperature and a predetermined low temperature, a valve closing member having an inoperable position spaced from said valve permitting opening and closing of the latter and yieldingly urged toward an operable position effective for mechanically closing said valve and maintaining it closed, electromagnetic means effective when energized for holding said valve closing member in inoperable position but ineffective for moving said member from its operable to its inoperable position, means responsive to a predetermined high temperature for releasing said valve closing member from said electromagnetic means, and reset means for moving said valve closing member from its operable to its inoperable position.

14. In control means of the character described, a valve body having an inlet chamber and an outlet chamber with a valve port therebetween, a valve controlling said port, thermostatic means

for mechanically opening and closing said valve to maintain selected temperatures, a valve closing member having an inoperable position permitting opening and closing of said valve and an operable position effective for mechanically closing of said valve and maintaining it closed, said valve having an extension and said member when in its inoperable position slidably receiving and guiding said extension and thereby guiding said

5 valve in its opening and closing, electromagnetic means effective when energized for holding said valve closing member in its inoperable position, and thermoresponsive means for releasing said valve closing member from said electromagnetic 10 15 means responsive to a predetermined temperature.

15. In control means of the character described, a valve body having an inlet chamber and an outlet chamber with a valve port therebetween, a valve controlling said port, thermostatic means 20 for mechanically opening and closing said valve to maintain selected temperatures, a valve closing member having an inoperable position permitting opening and closing of said valve and an operable position effective for mechanically closing of said valve and maintaining it closed, electromagnetic means effective when energized for holding said valve closing member in its inoperable position, and means effective for mechanically 25 urging said valve closing member away from said electromagnetic means with a force sufficient to release it therefrom.

16. In control means of the character described, a valve body having an inlet chamber and an outlet chamber with a valve port therebetween, a valve controlling said port, thermostatic means 30 for mechanically opening and closing said valve to maintain selected temperatures, a valve closing member having an inoperable position permitting opening and closing of said valve and an operable position effective for mechanically closing of said valve and maintaining it closed, electromagnetic means effective when energized for holding said valve closing member in its inoperable position, and means effective for mechanically 35 urging said valve closing member away from said electromagnetic means with a force sufficient to release it therefrom responsive to a predetermined temperature.

40 45 HAROLD A. MANTZ.
